United States Patent Office

Des. 194,280
Patented Dec. 25, 1962

194,280

COMBINED BOTTLE OPENER AND CAP HOLDING DEVICE

Robert J. Conners, Blue Ash, Ohio
(9016 Foxhunter Lane, Cincinnati, Ohio)

Filed Mar. 1, 1962, Ser. No. 69,038

Term of patent 14 years

(Cl. D44—29)

FIG. 1.

FIG. 2.

FIG. 3.

FIG. 4.

FIG. 5.

FIG. 1 is a plan view of a combined bottle opener and cap holding device, showing my new design;

FIG. 2 is a side elevational view thereof;

FIG. 3 is an end elevational view thereof with caps removed;

FIG. 4 is another end elevational view thereof; and

FIG. 5 is a view in section taken on the line 5—5 in FIG. 1.

I claim:

The ornamental design for a combined bottle opener and cap holding device, as shown.
